VOTING MACHINE WITH MECHANISM FOR
CUMULATIVE VOTINGRansom F. Shoup, Ardmore, Pa., assignor to The
Shoup Voting Machine Corporation, Philadelphia,
Pa., a corporation of Delaware

Application March 15, 1948, Serial No. 14,886

11 Claims. (Cl. 235—55)

1

This invention relates to voting machines and more especially to voting machines of the type covered by Shoup Patent No. 2,054,102.

In some jurisdictions, the election laws provide that with respect to certain offices, for example, representation in the general assembly each voter has the right to cast from one to three ballots for any candidate and also the voter has the right to distribute his three votes in any manner that he may desire among one to three candidates of his choice. Such provision is for the purpose of properly proportioning and balancing the relative strength of the political parties as it may be indicated in the general assembly. For example, the voter may cast his entire three votes for one candidate, or he may cast one and one-half votes for each of two candidates or he may cast a single vote for each of three of the candidates giving each of them one vote of the three votes allotted to him. To satisfy constitution provisions, the voter also must have the privilege of casting two votes for one candidate and one for another and also must have the privilege of distributing his three votes in any manner that he may desire as well as have the privilege of personal choice voting and the privilege of dividing his votes among his personal choice candidates in the same ways. As a further alternative, he must have the privilege of limiting his choice of candidates to a single party or of splitting his vote among candidates of two or more parties in such cases where he elects to divide his vote rather than to give the three votes to a single candidate. In other instances, the voter may have any other number of votes for distribution as he desires. For a voting machine to handle such type of cumulative voting at elections, it must be capable of being set up in such a manner that by manipulation of various of the voting levers opposite the names of candidates, or of personal choice mechanism or combinations of levers and personal choice mechanism, the voter would be able to distribute his vote in one of the ways just described and be precluded from performing any illegal voting.

It may be that after a voter has operated the machine to cast the votes to which he is legally entitled, he may attempt to operate one of the spindles which have been locked out as a result of his legal vote. The pressure available on such an attempt may provide sufficient leverage to register an illegal vote unless adequate provision is made to nullify the effect of such action.

An object of this invention is to provide mechanism for use in a voting machine of the character mentioned to enable it to be set up in such

2

a manner as to satisfy the requirements just discussed and by which the possibilities of illegal voting of the character described are eliminated.

Other objects, novel features and advantages of this invention will become apparent from the following specification and accompanying drawings wherein:

Fig. 1 is a fragmentary front view of a voting machine in which candidates for three different parties are listed in successive vertical columns to facilitate cumulative voting of the type described for a three vote situation, it being understood that candidates of other parties would be similarly listed in adjoining vertical columns, the said figure further illustrating in part the appearance of the machine as the voter enters the booth;

Fig. 2 is a similar view of the machine showing a voter's choice wherein he has divided his three votes evenly in a split ticket giving one and one-half votes to each of two candidates of two different parties by the operation of voting levers or handles;

Fig. 3 is a view similar to Figs. 1 and 2 illustrating a case wherein the voter has voted for three candidates of one party distributing his three votes to give one vote to each of the three candidates by the operation of voting levers or handles;

Fig. 4 is a fragmentary rear view of the frame of the voting machine showing the positions of parts when the voter has voted in the manner set up by the voter in Fig. 2 of the drawing;

Fig. 4A is an enlarged fragmentary view illustrating details of the illegal vote preventing mechanism showing parts in unvoted position;

Fig. 4B is a similar view showing the parts in voted position;

Fig. 5 is a rear view similar to Fig. 4 but illustrating the positions of parts when the voter has voted in accordance with the manner set up by him in Fig. 3 of the drawing;

Fig. 6 is a fragmentary section taken along line 6—6 of Fig. 5; and

Fig. 7 is an enlarged section taken along line 7—7 of Fig. 5.

In so far as practical, the reference characters used herein will correspond to the reference characters used in the specifications of Shoup Voting Machine patents such, for example, as Shoup et al. No. 2,054,102 and Shoup No. 2,191,036.

In the voting machine of Shoup et al. Patent No. 2,054,102, there are ten vertical columns of spindles and a main interlock together with interlock straps for connecting to the main inter-

lock the spindles of columns one to nine counting away from the interlock. Figs. 1 to 3 inclusive show all ten columns while Figs. 4 and 5 show only the first nine of such columns. The interlock straps for the spindles of these columns are of the variable length type shown and described in copending Shoup application, Serial No. 733,379, issued on August 29, 1950, as Patent Number 2,520,740.

Referring particularly to Fig. 6, the spindles 38 are journaled at one end in a plate 39 and at the other end are journaled in vertical straps 40. Each spindle is equipped with an operating handle 39 and is of square cross section except that it is provided with a circular groove 38a to be received in a circular bearing provided therefor in straps 40 and additional similar but narrower circular grooves 38b for other purposes. Each spindle 38 extends through and supports a channel member 60, the ends of which engage the plate 39 and a strap 40 and the channel member 60 is received within square apertures in two arms 59 and 59'. A rod 59b extends between and has its ends attached to the arms 59 and 59'. The plate 59a is attached to each arm 59' through the intermediary of the rod 59b which passes through a hole in arm 59' and a slot in the plate 59a. The plate 59a is thus slidably and rotatably connected to the arm 59' and is, therefore, capable of being adjusted to different positions relative to the arm as fully described in said Patent No. 2,191,086. By reason of the rectangular cross section of the channel member 60 and its snug fit on the square portion of the spindle 38, it is firmly secured to the spindle for rotation therewith. Likewise, rotation of the said spindle 38 causes rotation of the arms 59 and 59'. The arms 59 cooperate with their restoring frame 65 as described in said Patent No. 2,054,102 and the arms 59' and plates 59a cooperate with vertically and horizontally movable members 190 and straight ticket voting handles (not shown) in the manner described in said Shoup Patent No. 2,191,086.

A counter C is associated with each spindle 38 and is provided with a drive pinion 43 having a square aperture through which extends the square portion of the spindle 38. The counter C preferably is of construction described and claimed in the Shoup Patent No. 2,140,336.

Each rod 59b has connected therewith, one end of an interlock or pull strap 61 leading to a main interlock 42 of a construction described and claimed in Shoup Patent No. 2,191,086. In this interlock 42 are provided a plurality of interlock members 62, certain of which are tubular for the purpose of receiving pins 63 extending through apertures in the interlock casing for the purpose of fastening said members against movement relative to the casing of said interlock 42. Each interlock strap passes between a pair of interlock members 62 and is provided with a wedge 64 for spreading the two members apart.

In the wall 10, there is provided a vertical column of personal choice slots 139 with a slideable closure for each slot. One of such slots 139 is aligned with each of the horizontal rows of spindles 38. In back of the slots 139 is a guide table 141 over which passes a sheet of paper 142 from a feed roller 143 to a take-up roller (not shown). A yoke 150 pivotally supported on a vertical rod 150a is rotated counterclockwise from the position shown in Fig. 6 by movement of any closure 140 to its open position and, when actuated is returned to its original position upon return of the machine to curtain-open position by means (not shown)

but fully disclosed in said Shoup Patent No. 2,054,102. The yoke 150 cooperates with mechanism (not shown) to advance the strip 142 a predetermined distance for each actuation of the yoke.

The rod 150a is supported by brackets 150b attached to a vertical plate 150c in the shape shown in Fig. 6, and the plate 150c is provided with a vertical series of apertures constituting guideways for links 161 which at one end are attached to arms 160 pivotally supported by the rod 150a and each link is provided with a pin 61a connected to an interlock strap 61. Each of the arms 160 is provided with a head 160' projecting into a slotted channel shaped runner 222 having a right angle extension attached to a slide 223 supported by the wall 10. Each slide 223 is in alignment with a personal choice slot closure 140 so that movement of a personal choice slot closure into open position swings the arm 160 counterclockwise with consequent leftward movement of the corresponding link 161 and its associated interlock strap 61 to bring the wedge thereof between the rollers 62. Restoration of any actuated arm 160 and corresponding closure 140 is effected by mechanism for that purpose described in the Shoup et al. Patent No. 2,191,086.

On each spindle 38 is located an arm or butterfly B consisting of two plates 81 and 82 having square apertures of proper size snugly to receive the square portion of a spindle 38 and the apertures are so arranged that they register with each other only when the plates 81 and 82 are oriented with respect to each other and are out of register when the arms coincide so that they can be locked in desired position on a spindle 38. These arms forming the butterfly B are more particularly described in the copending Shoup application Serial No. 14,713, filed March 13, 1948, issued on January 31, 1950 as Patent Number 2,496,106. A stud or finger 85 extends from the butterfly B in a direction parallel with the spindle axes. This stud 85, as described in the last-named application, operates to lock the two plates 81 and 82 together and for other purposes presently to appear.

To satisfy the requirements of specific laws relative to cumulative voting in certain jurisdictions, the counters C of the spindles 38 must be so controlled that a voter by operation of the proper spindles can give his three votes to a chosen party candidate, or give one and one-half votes to each of two party candidates, or give one vote to each of three party candidates with appropriate of the counters C recording such votes in accord with the option afforded the voter, while precluding the possibilities of these counters recording votes in any other manner. Also to satisfy constitutional requirements, the machine must permit a voter to distribute his allotted votes as he shall see fit giving any number thereof to any desired candidate or candidates. The mechanism now to be described satisfies all of these requirements.

This mechanism comprises three plate members 550 of identical construction. Each such plate has a lateral upper flange 550a and a lateral lower flange 550b. Each of the plates has a length sufficient to span the number of voting columns or rows that it is desired to control. In the embodiment shown, each of said plate members has a length sufficient to span nine columns. Each may, however, be of any desired length so as to span as many of the vertical columns as are actually to be used. Each of the plate members

550 is provided with vertically arranged columns of generally rectangular apertures 551 so that a spindle 38 may pass through each such aperture. The left wall of each aperture 551 has an arcuate recess 552 at the bottom thereof for a purpose of eliminating illegal voting as will be described. Each aperture 551 also receives the pin or stud 85 associated with the butterfly B of the spindle 38 passing through the said aperture. The apertures are wide enough to permit necessary rotation of the spindles 38 and their studs 85 from non-voting to voting positions, and long enough to permit required sliding motion of said plates relative to the spindles projecting through the apertures. As seen clearly in Figs. 4 and 4A, the arcuate recess 552 is joined to the vertical portion 553 of left wall by a slanting portion 554 tangent to the arc defining the recess 552. In unvoted positions, each arm B extends downwardly toward the left below a line passing through its spindle axis parallel to the direction of the sliding motion available to the plate. In voted position, this arm extends upwardly to the left above this line. In the embodiment shown, each of the plates 550 has nine vertical rows of apertures 551, there being three of such apertures 551 in each vertical row. The three plates 550 are positioned at the rear of the machine one above the other with one spindle 38 projecting through each of the apertures 551 so that one of three adjacent groups I, II and III of spindles 38 in each of the nine columns (shown in Figs. 3 and 4) is controlled by each of the three plates 550.

Securing and guiding members 555 (Fig. 7) are provided to maintain the plates 550 in sliding relationship on the spindles 38 after they have been positioned thereon as has just been described. Each of these securing members 555 is provided with a pair of vertically aligned openings 555a whose centers are spaced apart a distance equal to the distance between the axes of any adjacent two spindles 38 in a vertical row so that the securing members 555 may be slid onto such pairs of spindles 38 after the positioning of the plate members 550 thereon. A locking arm 556 similar to plate 81 having a square aperture to permit the passage therethrough of one of the spindles 38 is mounted on the top one of the two spindles 38 projecting through the member 555 and then offset in one of the grooves 38b of the said spindle 38 and locked in such position by means of the stud or pin 557 which is screwed into a threaded hole in the member 555, thereby effectively locking the arm 556 and securing member 555 in place on the spindle 38 and preventing removal of the plates 551 from such spindles. Spacing members 558 and guide rollers 558a are supported from member 555 at spaced apart positions by the pins or rivets 559 and extend rearwardly of the latter with one guide roller 558a lying in each of two adjacent apertures 551 of the plate member 550. The rollers 558a are spaced apart by the pins 559 a distance equal substantially to the width of the bridging portion 550c between the apertures 551 into which they extend. These rollers function as guides which prevent material vertical motion of the plate members 550 when positioned on the spindles but permit lateral translation or sliding movement of said plates in a horizontal direction. The spacing members 558 prevent movement of the plate members 550 toward the securing members 555 in the axial direction of spindles 38 while the butterflies B lying just behind the plates 550 prevent similar movement away from the member

555. Any desired number of securing members may be used with each plate 550.

A biasing spring 560 has its opposite ends 560a and 560b secured respectively to one of the securing members 555 and to the plate 550. One biasing spring 560 is provided for each of the plates 550 and each of the latter is biased normally in the direction toward the right of Figs. 4 and 5 to a fixed position which is the limit of rightward movement permitted by engagement of studs 85 with the arcuate recesses 552. Other equivalent means for effecting this biasing action and also for securing the plates 550 in slidable relationship on the spindles 38 may, of course, be used instead of the means described.

Each of plates 550 has a right angled flange 565 secured thereto as by pins 566 and 567. This flange is so positioned as to project into the path of travel of pins 61a of the personal choice closures aligned with the spindles such plate controls. Leftward movement of any of such pins 61a results in leftward movement of the plate, the flange 565 of which it engages.

The interlock straps 61 of all the group I spindles and personal choice slides aligned therewith are connected in a group I portion of the main interlock 42 which is set up for one vote condition. The interlock straps 61 of all the group II spindles and personal choice slides aligned therewith are connected in a group II portion of the main interlock 42 which is set up for a vote two condition. The interlock straps 61 of all the group III spindles and personal choice slides aligned therewith are connected in a group III portion of the main interlock 42 which is set up for a vote three condition, all for the purposes to be described.

A supplementary interlock 42' of substantially similar construction to the main interlock 42 is secured to one side of the machine, for example, the right-hand side as shown in Figs. 4, 5 and 6. This supplementary interlock 42' has a plurality of interlock members 62', certain of which are tubular for the purpose of receiving pins 63' extending through apertures in the supplementary interlock casing for the purpose of fastening said tubular member 62' against movement relative to the casing. An interlock strap 61' has one of its ends connected to one of the plates 550 and its other end is provided with a wedge 64'. There are three such interlock straps 61' provided, one for each of the plates 550. Each of these three interlock straps 61' passes between a pair of the interlock members 62' so that the wedge 64' on any one of the three may be moved to spread such interlock members 62' apart. The supplementary interlock 42' is set up for one vote conditions. It thereby prevents similar movement of the wedges 64' of the other two of said interlock straps, thereby locking out the plates 550 connected to said other two interlock straps. In consequence, the shifting of any one of the three plates 550 toward the left of Figs. 4, 5 and 6 in a manner presently to be described will lock out the other two such plates 550 and prevent operation of spindles 38 upon which such two plates are positioned, thereby providing for voting in accordance with the requirements set forth at the outset of this specification.

In the normal position of the parts when a voter enters the booth and observes the set-up shown in Fig. 1 before any of the individual voting handles 39 has been actuated, all three of the plates 550 lie at their extreme right-hand positions under the biasing action of their re-

spective biasing springs 569. In such condition, the butterflies B of the respective spindles 38 all lie in lowered positions, for example, the position of the butterfly B in Fig. 4A. The pin or stud 85 of such butterfly B then lies in the arcuate recess 552 below a line passing through its spindle parallel to the direction of sliding motion of plates 550. If the voter desires to cast all three of his votes for one of the three candidates listed in the upper group I in the first column of Fig. 1, for example, Smith, he rotates the voting handle 30 opposite the name of Smith in group I to voting position. The rotation of this voting handle 30 to this position rotates its spindle 38 and its butterfly B to a raised position above said line as seen in Fig. 4B to cause a lateral shift or slide of the uppermost plate 550 transversely of the spindle axis and toward the left against the action of its biasing spring 560. This movement of plate 550 occurs because rotation of the particular spindle 38 causes its stud 85 to move out of its arcuate recess 552 against the biasing action of spring 560 exerting a thrust first on the slanting wall 553 and then on the straight portion 554 of the left side of the aperture 551 of the particular spindle 38. This same action causes the interlock strap 61' of the upper plate 550 to move toward the left to bring its wedge 64' into a spreading position between two of the interlock members 62'. At the same time 30 the interlock strap 61 actuated by the arm 59 and the rod 59b of the rotated voting spindle will cause its wedge 64 to move into spreading apart position between two of the interlock members 62 in the group I portion of the main interlock 42 which is set up for one vote operation, thereby precluding further operation of any of the other spindles 38 in the uppermost or group I rows of spindles or any of the personal choice closures 140 of group I to an open position. The described movement of the interlock strap 61' of the uppermost plate 550 in relation to supplementary interlock 42' which is also set up for one vote operation, similarly locks out the two lower plates 550 against longitudinal shift because the wedges of their interlock straps 61' cannot now enter between a pair of interlock members 62'. This precludes the operation of any of the spindles 38 allocated to any of the groups II and III of spindles 38 bearing the said two lower plates 550 because the studs 85 on the butterflies B of these spindles 38 are engaged in the arcuate recesses of the two lower plates 550 which are locked against movement. Also because pins 61a of the group II and group III personal choice closures 140 engage flanges 565 of the group II and group III plates 550, said closures are locked out against any opening movement. The voter, therefore, is precluded from casting any additional votes other than the single vote he has effected by movement of the one voting handle 30 in group I which has had the effect of casting, for example, three votes for Smith. He could, of course, have voted for any other single candidate of any party in group I instead of Smith with the same action resulting. Instead he could give only one personal choice candidate three votes by moving one of the three personal choice closures alined with the group I rows of spindles to open position and by writing in the name of such candidate on the paper 142 under the opened slot. This action would cause leftward movement of pin 61a of the closure opened and leftward movement of the upper or group I

70 75

plate 550 locking out the other two plates 550. The leftward movement of the particular pin 61a would also draw the interlock strap 61 connected thereto into interlock 42 and lock out all spindles 38 in group I and the other two personal choice closures 140 slides of this group.

Should the voter instead desire to cast one and one-half votes, for each of two candidates, he must utilize the spindles 30 in group II or two personal choice closures 140 alined with group II. For example, to give one and one-half votes to the party Brown and one and one-half votes to the party Lee, both of whose names appear in group II under different party headings, he manipulates the voting spindles 30 opposite these two names in group II of Fig. 2. The group II portion of the main interlock 42 is set up for two vote operation as described. The interlock straps 61 of all the spindles 38 and personal choice closures 140 allocated to group II are all connected to the two vote (group II) portion of the main interlock 42 so that any two and only two such spindles, or any two and only two personal choice closures alined with group II spindles or one spindle and one personal choice closure of group II can be operated by the voter. The operation of the first spindle in group II, by virtue of the interaction of the stud 85 on its butterfly B or the operation of the first personal choice closure 140 in group II by action of its pin 61a, has the effect of shifting the second or intermediate plate 550 to the left against the action of its biasing spring 560, as shown in Fig. 4, causing the interlock strap 61' of the latter plate 550 to move into locking position with respect to the supplementary interlock 42'. Since the latter is set up for one vote operation, the two plates 550 of the groups I and III are locked out and this precludes any operation of any voting spindle 38 or any personal choice closure 140 allocated to either of said two groups I and III. The voter then may vote for a second candidate in group II but no more. He can then operate one more spindle 38, or one more personal choice closure of group II but only one of them to record an additional vote. Thus, the voter is able only to vote for two candidates in group II giving each one and one-half votes and is unable in any way to cast additional votes for any other candidate. The position of the voting handles 30 of the two candidates Brown and Lee, for example, for whom the voter has cast his vote, as shown in Fig. 2, operates their spindles 38 to move their butterflies B to their vote indicating positions shown in Fig. 4 in the columns marked 2 and 3 and shifts the plate 550 of said group II to the position shown in Fig. 4. One and one-half votes for each is the result.

On the other hand, should the voter decide to vote for three candidates giving each one vote, or desire to give two votes to one and a third for another, he must utilize the spindles 38 or personal choice closures in group III as set up on the voting machine. The group III portion of the main interlock is set up for three vote operation as described. The interlock straps 61 of all the spindles of group III and personal choice closures 140 alined therewith are all connected to three vote (group III) portion of the main interlock 42 so that any three of said spindles 38 or any two thereof and one personal choice closure 140, or any one thereof and any two personal choice closures 140, or all three personal choice closures of this group III can be operated by the voter to record three votes. The operation of the first one of any of the voting handles 30 in group III

causes its butterfly B as seen in Fig. 5 to be rotated from a normal lowered position to the raised voting position shown in Fig. 5, wherein its stud 85 has moved out of the arcuate portion 552 onto the straight portion of the left wall of aperture 551 and has caused a longitudinal shift to the left as seen in Fig. 5 of the plate 550 associated with group III. A movement of any one of the three personal choice closures 140 of group III by action of the pin 61a associated therewith will cause a similar shift to the left of plate 550 of group III. This longitudinal shift of the said group III plate 550 toward the left has caused its interlock strap 61' to move toward the left and has drawn its wedge into a spreading position between a pair of interlock members 62' of the supplementary interlock 42'. Such action effectively locks the other two plates 550 of groups I and II against movement and precludes operation of any of the voting spindles 38 or personal choice closures 140 allocated to groups I and II. Thus, the voter after having operated one of the spindles or one of the personal choice closures 140 of group III cannot operate any spindle of personal choice closure allocated to either of groups I or II. He may, however, still cast two more votes in group III either by rotating two additional voting spindles 38 in the group III or operating two more personal choice closures 140 of this group III or operating one more spindle and one more personal choice closure 140 of this group III so as to cast two additional votes one for each of two more candidates, for example, the candidates David and Brown in group III, column 2 of Fig. 3. As soon as these two additional votes are cast, the interaction of the main interlock straps 61 of this group III with the main interlock 42 precludes further operation of any additional group III spindles or personal choice closures of this group.

With the mechanism consisting of the three plates 550 and the supplementary interlock 42', it thus becomes possible for a voter to select one candidate only of any party or a personal choice candidate and give him three votes or to select any two candidates of the parties running or personal choice candidates giving each one and one-half votes, or to select any three candidates of the parties running or personal choice candidates giving each one vote. With respect to the latter two selections, the voter may split his ticket as desired not being restricted to choosing all the candidates of a single party and may, in fact, give one candidate two votes and another one vote if he desires. Should the voter desire, instead, to exercise the latter option, he would use the group III spindles and/or personal choice closures of this group. To give one party candidate two votes he would operate the voting spindle opposite that candidate's name in group III to voting position and then operate a personal closure 140 of group III to an open position to expose the paper 142 and write in the same candidate's name. He then can operate either another spindle or another personal choice closure to give one additional vote to another candidate. He could give a personal choice candidate two votes by operating two personal choice closures 140 of group III to open position and writing the same candidate's name twice once in the paper exposed by each personal choice closure. Then he could cast one more vote for another candidate by operating either a spindle in group III or the third personal choice closure 140 of group III. The position of the write-in

votes on the paper 142 exposed by opening movement of the said personal choice closures indicates the number of votes to be accorded to the write-in candidate. If it lies in the group I position he gets three votes; if in the group II position one and one-half votes and if in the group III position then one vote each time his name appears.

It may happen that after a voter has operated a personal choice closure 140 to draw the wedge of the personal choice interlock strap 61 into main interlock 42 or after he has operated one of the spindles of the three groups, that he may attempt to operate one or more of the spindles 15 associated with the locked out plates 550 of the groups which he may not then use legally. Such attempts would result in pressure being applied to the locked out plates 550 with which such spindles are associated tending to move them to permit sufficient rotation of the improperly operated spindles to operate the counters associated therewith, thereby allowing the voter to vote for more candidates than he is legally entitled to. The arcuate recesses 552, however, decrease the leverage which a voter can apply to any of the three plates 550 through procedure as above described, thereby eliminating the possibility of buckling of the plates 550 and of any illegal voting operations in the machine. The securing members 555 also serve to prevent outward movement of the plates 550 which might result in enough play to permit improper operation of the spindles 38. The provision, therefore, of the arcuate recesses 552 and the securing members 35 555 or their equivalents is of vital importance in order to provide a practical machine in which illegal voting is absolutely prevented.

Should the voter change his mind after setting up his votes, either all spindle operated or a mixture of spindle and personal choice votes, if he has voted only by using spindles, he could change his entire vote by restoring all actuated voting handles to original condition and start over again since the biasing springs would then restore all plate members 550 to initial condition. If, however, he has mixed spindle votes and personal choice votes, he can only change the spindle votes by restoring the handles of the voted spindles to unvoted position and operating other voting handles 30 in the same group corresponding in number to the restored number of handles, or operate previously unused personal choice closures 140 in the same group limited to the remainder of the total he is entitled to actuate in the particular group. He could, of course, erase a previously written-in name and write another in its place.

Were the situation such that the voter had a vote four cumulative choice, the plates 550 would 60 each have vertical columns of four apertures 551 and each plate would overlie four horizontal rows of spindles. Four such plates would then be required and four groups of names in each vertical column would have to be set up on the front face of the voting machine. Similarly, if he had a vote five cumulative choice, the plates 550 would each have vertical columns of five apertures 65 and each plate would overlie five horizontal rows of spindles. Five such plates would then be required. In other words, the number of plates required corresponds to the votes available to the voter and the number of apertures required in each such plate corresponds to the 70 same number of votes. Similarly, the number of

groups of names set up on the face of the machine corresponds to the same number of votes.

With respect to the apertures 551, each is also of sufficient length to permit mechanical adjustment of parts such as arms 59 and 59' behind the plates 550 without the necessity of removing the plates. Each, of course, is of sufficient width or height to permit rotation of the voting spindles 39 from unvoted to voted positions.

While specific embodiments of the invention have been described, variations in detail and in the scope of the claims are possible and are contemplated. There is no intention, therefore, of limitation to the exact details shown and described.

What is claimed is:

1. In a voting machine, voting spindles, butterflies, one secured to each spindle, a finger on each butterfly extending parallel to the spindle axis, and mechanism for cumulative voting comprising plate members, slideable at right angles to said spindles, each plate member having vertical columns of apertures for passage through each of one of said spindles and one of said fingers, said plate members being independently slideable by the action of any one of the fingers of any one of the spindles associated with such plate member upon rotation of such spindle to vote indicating position, the number of plate members and the number of apertures in the vertical columns of each plate member corresponding to the votes available to the voter, a main interlock, interlock straps, one coupling each finger with said main interlock, a supplementary interlock, interlock straps, one coupling each of said plate members with said supplementary interlock, biasing means for each plate member for biasing it in a determined direction and means for precluding illegal voting upon attempted operation of any spindles locked out by locked-out plates by actuation of the machine in accord with the vote available to the voter said last named means including an arcuate recess in each aperture in which the finger passing through such aperture is normally positioned in the unvoted condition of its voting spindle by the action of said biasing means, a slanting surface adjoining the arcuate recess and inclined toward the axis of the spindle passing through the aperture from a point below and to one side of the said axis and a straight surface adjoining said slanting surface.

2. In a device as per claim 1 securing means for substantially precluding movement of said plate members longitudinally of the spindles and for guiding said plate members on the spindles over which they are mounted for sliding motion transversely of the spindle axes, said securing means comprising securing members, and guide rollers rotatably attached to said securing members and engageable with portions of said plate members.

3. In a device as per claim 2 in which said guide rollers are spaced apart, each extending into a different one of the apertures and into engagement with a wall portion thereof.

4. In a voting machine, voting spindles, arms, one secured to each spindle, a finger on each arm extending parallel to the spindle axes, and mechanism for cumulative voting comprising members slideable at right angles to said spindles, each member having apertures for passage through each of one of said spindles and one of said fingers, said members each being independently slideable at right angles to the axes

of the spindles passing through its apertures upon rotation of any one of such spindles to vote indicating position by action of the finger of such a rotated spindle, main interlock means, and supplemental interlock means coupled to each of said plate members to permit sliding movement of only one of such members at a time and lockout the other plate members and thereby to lock out all spindles relative to which the locked out of said plate members are slideable against vote indicating rotation, said main interlock being coupled to the said spindles to prevent voting operation of more than a selected number of the spindles relative to which the moved of said plate members is slideable, and said apertures each having a recess in which the finger passing therethrough normally engages to reduce leverages available sufficiently upon attempted actuation of any locked out spindles to preclude all illegal voting, a slanting surface adjoining the recess and inclined toward the axis of the spindle passing through the aperture from a point below and to one side of said axis and a straight surface adjoining said slanting surface.

5. In a voting machine, rows of voting spindles, a butterfly fixed to each spindle, a finger on each butterfly extending parallel to the spindle axis, a plate member slideable at right angles to said spindles and having apertures through each of which one of said spindles passes, said plate member being slideable by the action of one of said fingers upon rotation of its spindle to vote indicating position, a main interlock, interlock straps one connecting each spindle with said main interlock, a supplementary interlock, and an interlock strap connecting said plate member with said supplementary interlock, additional identical plate members slideable at right angles to said spindles and each having apertures for passage through each of other ones of said spindles, and additional interlock straps, one of the latter interlock straps connecting each of said identical plate members with said supplementary interlock whereby operation of any of said spindles to a vote indicating position will slide the plate member borne thereon to a position relative to the supplementary interlock that will lock the other identical plate members against movement and thereby lock out and preclude vote indication movement of all spindles associated with the locked out plate members, said apertures each having an arcuate wall portion, a slanting wall portion adjoining the arcuate portion and inclined toward the axis of the spindle passing through the aperture from a point below and to one side of the latter axis, and a straight wall portion adjoining the slanting wall portion, the finger passing through each such aperture in the unvoted condition of its spindle normally lying in contact with the arcuate wall portion of such aperture and being required in the movement of the latter named spindle to voting position to move over the slanting wall portion onto the straight wall portion of its aperture in order to slide the plate member bearing the latter aperture to lock out the other plate members and thereby preclude illegal voting operation of spindles associated with the locked out plate members.

6. In a voting machine, voting spindles, arms, one secured to each spindle, a finger on each arm extending parallel to the spindle axis, and mechanism for cumulative voting comprising plate members slideable at right angles to said spindles, each plate member having apertures

for passage through each aperture of one spindle of a group of said spindles, said plate members each being independently slidable relative to the spindles of a group passing through plate member apertures by the action of any one of the fingers of any one of such group of spindles upon rotation of such spindle to vote indicating position, biasing means for the plate members for biasing each to a determined position, a main interlock, interlock straps, one coupling each 10 spindle of the groups of said spindles with said main interlock, a supplementary interlock, supplementary interlock straps, one coupling each of said plate members with said supplementary interlock, said supplemental interlock being set up 15 to permit sliding movement of only one of said plate members at a time away from the determined position, and to lock out the others of said plate members, and said main interlock being set up to preclude operation by the voter to a 20 vote indicating position of more than a fixed number of the spindles of the group of such spindles passing through apertures in the moved of said plate members, said apertures each having an arcuate wall portion, a slanting wall portion adjoining the arcuate portion and inclined toward the axis of the spindle passing through the aperture from a point below and to one side of the latter axis, and a straight wall portion adjoining the slanting wall portion, the finger passing through each such aperture in the unvoted condition of its spindle normally lying in contact with the arcuate wall portion of such aperture and being required in the movement of the latter 25 named spindle to voting position to move over the slanting wall portion onto the straight wall portion of its aperture in order to slide the plate member bearing the latter aperture to lock out the other plate members and thereby preclude illegal voting operation of spindles associated with the locked out plate members.

7. In a voting machine having a plurality of spindles and means for limiting the extent of rotation of each spindle between voted and unvoted positions, mechanism for conditioning said machine for cumulative voting with said spindles divided into a plurality of multiple spindle groups, said mechanism comprising a plate for each group supported for reciprocation transversely of the axes of said spindles between a first position and a second position, means for biasing each plate for movement into its first position, each said plate having a plurality of apertures having surfaces perpendicular to its direction of reciprocation, a plurality of arcuate surfaces and a plurality of slanting surfaces one joining each arcuate surface with one of the first named surfaces, a finger carried by each spindle for projecting through an aperture and for engagement with a said arcuate surface each said slanting surface being inclined toward the axis of the spindle passing through the respective aperture from a point below and to one side of the latter spindle axis said finger being movable from such engagement over a said slanting surface and onto a said perpendicular surface to effect movement of said plate from its first position to its second position and partially back toward its first position under the influence of said biasing means upon movement of said spindle from its unvoted position to its voting position, said finger being so arranged with respect to the spindle axis that in unvoted position of the spindle the finger lies on one side of a line passing through the spindle axis parallel to the direction of reciprocation of said plate and

against the arcuate surface and lies on the opposite side of said line in the voted position of said spindle, passing over the said slanting surface in its movement to the voted position, an auxiliary interlock for the set of plates responsive to actuation of one plate to prevent actuation of any remaining plate, and another interlock for the group of spindles associated with each plate effective upon actuation of a predetermined number of spindles of said group.

8. In a voting machine having a plurality of spindles and means for limiting the extent of rotation of each spindle between voted and unvoted position, mechanism for conditioning said machine for cumulative voting with said spindles divided into a plurality of multiple spindle groups, said mechanism comprising a plate for each group supported for reciprocation transversely of the axes of said spindles between a first position and a second position and biased for movement into said first position, biasing means for the plate, said plate having a plurality of apertures having surfaces perpendicular to its direction of reciprocation, a plurality of arcuate surfaces and a plurality of slanting surfaces one joining each arcuate surface with one of the first named surfaces, a finger carried by each spindle for projecting through an aperture and for engagement with each said slanting surface being inclined toward the axis of the spindle passing through the respective aperture from a point below and to one side of the axis of the latter-named spindle, a said arcuate surface and movable from such engagement over a said slanting surface and onto a said perpendicular surface to effect movement of said plate from its first position to its second position and partially back toward its first position under the influence of said biasing means upon movement of said spindle from its unvoted position to its voting position, said finger being so arranged with respect to the spindle axis that in unvoted position of the spindle the finger lies on one side of a line passing through the spindle axis parallel to the direction of reciprocation of said plate and against the arcuate surface and lies on the opposite side of said line in the voted position of said spindle, passing over the said slanting surface in its movement to the voted position, a group of personal choice slide members 45 for each group of spindles, means for effecting movement of a plate from its first to its second position upon actuation of a personal choice slide member allocated thereto, a supplemental interlock for the set of plates responsive to actuation 50 of one plate to prevent actuation of any remaining plate, and a main interlock having a different individual auxiliary interlock portion for the set of spindle and slide members associated with each plate effective upon actuation of a predetermined 55 number of members of said set, each auxiliary interlock portion being arranged to permit the actuation of a number of spindle and slide members of its set different from any other set, and said arcuate and slanting surfaces serving to 60 minimize plate moving pressure available to a voter for operation of the fingers of the spindles allocated to the plates whose actuation is prevented upon any attempts to move the latter spindles to voted positions thereby preventing illegal voting.

9. In a voting machine having a spindle and means for limiting the extent of rotation of said spindle about its axis between voted and unvoted positions, a plate supported for reciprocation 65 transversely of the axis of said spindle between

a first position and a second position, means for biasing said plate for movement into said first position, said plate having an aperture with a surface perpendicular to the direction of reciprocation of the plate, an arcuate surface, and a slanting surface joining the arcuate surface with said perpendicular surface, a finger carried by said spindle for engagement with said arcuate surface in the first position of said plate member, said slanting surface being inclined toward the axis of said spindle from a point below and to one side of the axis of said spindle, and said finger being movable from its engagement with said arcuate surface over said slanting surface and onto said perpendicular surface to effect movement of said plate member from its first position to its second position and partially back towards its first position under the influence of said biasing means upon movement of said spindle from its unvoted position to its voted position, said finger being so arranged with respect to the spindle axis that in unvoted position of the spindle the finger lies on one side of a line passing through the spindle axis parallel to the direction of reciprocation of said plate and against the arcuate surface and lies on the opposite side of said line in the voted position of said spindle and against said perpendicular surface.

10. In a voting machine, a voting spindle movable between unvoted and voted positions, a finger connected to said spindle and extending parallel to the axis of the spindle, and a plate member slidable at right angles to said spindle, said plate member having an aperture for passage through it of said spindle and said finger, said aperture having a wall substantially perpendicular to the direction of slide of said plate member, an arcuate wall and a slanting wall joining the perpendicular wall to the arcuate wall and being inclined toward the axis of said spindle from a point below and to one side of said axis, biasing means for biasing said walls toward said finger and said finger being positioned relative to said spindle so as to lie in contact with said arcuate wall in the unvoted position of said spindle and being movable along 45 said slanting wall and onto said perpendicular

wall in movement of said spindle from unvoted to voted position for effecting a sliding movement of said plate member at right angles to said spindle.

- 5 11. In a voting machine, voting spindles each movable between unvoted and voted positions, fingers one connected to each spindle and each extending parallel to the axis of the spindle to which it is connected, plate members slidable at 10 right angles to said spindles, said plate members each having apertures for passage through each of one of a selected group of said spindles and of the finger connected therewith, each aperture having a wall substantially perpendicular to the direction of slide of the plate member bearing it, an arcuate wall and slanting wall joining the perpendicular wall to the arcuate wall and being inclined toward the axis of the spindle passing through the particular aperture from a point below and to one side of said axis, biasing means for biasing the walls of such aperture toward the particular finger passing through such aperture, each finger being positioned relative to its spindle so as to lie in contact with the arcuate wall of the aperture through which it passes in the unvoted positions of said spindles and being movable along the slanting wall of its aperture and onto the perpendicular wall of its aperture in movement of the spindle with which it is connected from unvoted to voted position for effecting a sliding movement of the plate bearing the aperture of the latter spindle at right angles to the latter spindle.
